G. W. Dawson,

Musical Game.

No. 97.612.

Patented Dec. 7, 1869.

Witnesses

W. H. Shumway
A. J. Libbets

George W. Dawson

Procurator

By his Attorney.

John S. East

United States Patent Office.

GEORGE W. DAWSON, OF NEW HAVEN, CONNECTICUT, ASSIGNOR TO WILLIS M. SMITH, OF SAME PLACE.

Letters Patent No. 97,612, dated December 7, 1869.

MUSICAL GAME.

The Schedule referred to in these Letters Patent and making part of the same.

To all whom it may concern:

Be it known that I, GEORGE W. DAWSON, of New Haven, in the county of New Haven, and State of Connecticut, have invented a new Musical Game; and I do hereby declare the following, when taken in connection with the accompanying drawing, to be a full, clear, and exact description of the same, and which said drawing constitutes part of this specification, and represents a top view of the board upon which the game is to be played.

This invention has for its object both amusement and instruction, designing by the game to teach the letters or notes and points in music; and

The invention consists in the arrangement, upon a board of two parts, one treble and the other bass, divided into squares in similar manner as for the game of checkers, and as shown in the accompanying drawing, each of the squares being marked with the letter or note which belongs to it in its relative position.

The squares are placed, three on each line, and three on each space of the staves, also above and below the staves. Each square is lettered, and the same as if it were a musical note. The game is played similar to checkers, excepting when sharps or flats are used.

In using sharps or flats, each player must be careful, and not let his or her opponent jump a man on the sharp or flat-line or space.

For example, we will take the key of G. F is the letter which is always sharp in this key. Each player must be careful, and not let his or her opponent jump a man on the letters F, and so on in the sharped and flattened letters of other keys. If either player is lucky enough to jump one or more men, and one of them is on a sharped or flattened line, he or she is entitled to take one more man than is jumped, picking it out anywhere he or she may choose from the loser's men.

The players can use any number of sharps or flats they may choose, following the above directions in regard to the sharped and flattened letters. The players can change from the bass to the treble staves as they choose.

The men employed in the play are similar to those used in playing checkers.

I claim, as my invention—

The herein-described musical game.

GEO. W. DAWSON.

Witnesses:

A. J. TIEBITS,
J. H. SHUMWAY.